Primary Examiner — Cynthia Ramirez*(74) Attorney, Agent, or Firm* — Cook Alex Ltd.(57) **CLAIM**

We claim the ornamental design for a pallet truck, as shown and described.

DESCRIPTION

FIG. 1 is a rear perspective view of a pallet truck according to our new design;

FIG. 2 is a front perspective view thereof;

FIG. 3 is a rear elevational view thereof;

FIG. 4 is a right side elevational view thereof;

FIG. 5 is a front elevational view thereof;

FIG. 6 is a left side elevational view thereof;

FIG. 7 is a top plan view thereof; and,

FIG. 8 is a bottom plan view thereof.

The broken line showing in the figures is included for the purpose of illustrating portions of the pallet truck and forms no part of the claimed design.
